UNITED STATES PATENT OFFICE.

FRANK S. BENNETT, OF SCHENECTADY, NEW YORK, ASSIGNOR TO GENERAL ELECTRIC COMPANY, A CORPORATION OF NEW YORK.

GOVERNING MECHANISM.

Application filed May 26, 1920. Serial No. 384,423.

To all whom it may concern:

Be it known that I, FRANK S. BENNETT, a citizen of the United States, residing at Schenectady, in the county of Schenectady, State of New York, have invented certain new and useful Improvements in Governing Mechanisms, of which the following is a specification.

The present invention relates to governing mechanisms, such as are used to control the admission of elastic fluid to prime movers and has for its object to provide an improved structure and arrangement in such a mechanism.

15 In the following specification, I have particularly described my invention as applied to an elastic fluid turbine but it will be understood that it is not necessarily limited to such use.

20 In the drawing, Fig. 1 is a diagrammatic view of a governing mechanism embodying my invention, and Fig. 2 is a perspective view of certain parts.

Referring to the drawing, 5 indicates an elastic fluid turbine to which high pressure elastic fluid is supplied through a conduit 6. In conduit 6 is an emergency trip valve 7, a manually operated control valve 8, and a governor controlled valve 9.

30 Emergency valve 7 may be of any suitable type and in the present instance is shown as being a simple flap valve pivoted on a spindle 10 which carries a lever arm 11, to which is fastened one end of a trip rod 12.

35 Trip rod 12 is provided at its other end with a catch plate 13 adapted to engage a catch 14 formed on a shaft 15. Rod 12 is guided at its free end by a bracket 16 loosely mounted on shaft 15, the rod 12 passing

40 through an opening in an arm of bracket 16 and under a pin 17 which projects from bracket 16. On rod 12 is a collar 18, and surrounding the rod is a spring 19 which at one end presses against collar 18 and at the other end engages bracket 16. This

45 spring acts to bias valve 7 toward the closed position. When the parts are in the position shown in Figs. 1 and 2, catch plate 13 is in engagement with catch 14 and valve 7 is held open against the action of spring 19. When shaft 15 is turned in a clockwise direction, as shown in Fig. 1, the catch plate 13 will be released to permit spring

50 19 to close valve 7. Catch 14 is held in engagement with catch plate 13 by a spring 20,

one end of which is connected to a lever arm 21, projecting from shaft 15 and the other end of which is connected to a fixed abutment indicated at 22. Carried by shaft 15 is a bifurcated lever 23 having a pin at its outer end which passes through elongated slot in the upper end of a trip rod 24. Trip rod 24 is guided by a casing 25 in which is a spring 26 which tends to force rod 24 downward to turn shaft 15 in a direction to release catch 14. Rod 24 is held upward against the action of spring 26 by a trip finger 27 pivoted at 27. Trip finger 27 is located adjacent shaft 28 of the turbine 5. Carried by shaft 28 is a spring controlled plunger which, when the speed of the turbine exceeds a predetermined amount, is thrown out by centrifugal force to strike the end of trip finger 27, thereby knocking it from under rod 24 and permitting spring 26 to force rod 24 downward to turn shaft 15 and release catch 14, thereby permitting spring 19 to close valve 7. On shaft 15 is a handle 30 for use in resetting the mechanism and also for use in tripping it manually.

An emergency trip mechanism as just described is a known arrangement and is illustrated in a diagrammatic manner only.

Manually operated valve 8 may be of any suitable type and in the present instance is shown as being a well known type of valve, provided with a pilot valve to assist in opening the same. It is operated by means of a hand lever 31, which moves over quadrant 32.

Governor operated valve 9 is shown as being a balanced valve and has its stem 33 connected to a piston 34 which moves in a cylinder 35. In cylinder 35 is a spring 36 which normally presses against piston 34 and biases valve 9 toward closed position. Connected to cylinder 35 on the side of piston 34 opposite to that on which spring 36 is located, is passage 37 formed in a pilot valve casing 38. In pilot valve casing 38 is a cylindrical sleeve 39 having ports 40 which communicate with passage 37 and also ports 41 which communicate with an inlet chamber 43 formed in pilot valve casing 38. In pilot valve casing 38 is a discharge chamber 44 with which the lower open end of sleeve 39 communicates. Adjacent inlet chamber 43 is a supply chamber 45 to which is connected a fluid pressure sup-

100

105

110

ply pipe 46, and the flow of fluid from supply chamber 45 to inlet chamber 46 is under the control of a valve 47. It will be understood that inlet passage 37 and inlet chamber 43 entirely surround pilot valve sleeve 39 so that such passage and chamber communicate directly with the ports 40, and 41 entirely around the circumference of sleeve 39. In the wall which separates inlet passage 37 from discharge chamber 44 is an opening 48 controlled by a valve 49 which is connected to valve 47 by a stem 50. Valve 47 is normally held open and valve 49 is held closed by a pivoted lever 51, one end of which bears yieldingly against valve 49 through the intermediary of a suitable spring 51^a and the other end of which is connected to one end of a rod 52, the other end of which is provided with a head having a catch 53 adapted to engage with a latch 54 fixed on shaft 15. Catch 53 and latch 54 are normally held in engagement with each other by a curved leaf spring 55, which spring also serves to guide the movements of rod 52.

In a sleeve 39 is a pilot valve 56 which normally covers ports 40 and has its stem 57 connected to one end of a floating lever 58, the other end of such lever being connected by a rod 59 to a floating governor lever 60. At an intermediate point floating lever 58 is pivoted, as indicated at 61, to the elbow of a bell crank lever 62, one arm of which is pivoted on a fixed bracket 63 and the other arm of which is connected by a link 64 to valve stem 38. This forms a usual type of follow-up device for the governor controlled valve mechanism, as will be pointed out hereinafter.

The other end of floating governor lever 60 is connected to the stem 65 of a piston 66 which moves in a cylinder 67, such movement taking place between stop shoulders 68 and 69. Piston 66 is normally held down against stop shoulder 68 by an adjustable governor spring 70 which spring is under tension. Connected to cylinder 67 on the same side of piston 66 as is spring 70, is a pressure pipe 71 which is supplied with fluid at a pressure which bears a definite relation to the speed of the turbine 5. In the present instance, pressure pipe 71 is shown as being connected through a non-return valve 72 to a suitable pump 73, here indicated as being a gear pump driven from turbine shaft 28 by a counter shaft 74 through a worm gearing, as indicated at 75. The conduit 46 which supplies fluid pressure for operating the fluid actuated motor which moves valve 9 is shown also as being connected to pump 73 through a suitable non-return valve 76, this being a convenient source of fluid pressure for such motor. Worm gearing 75 also drives a speed governor 77 having a spindle 78, the upper end of which is pivoted to

governor lever 60 through a suitable connection as indicated at 79 which permits spindle 78 to rotate relatively to lever 60 and also permits lever 60 to pivot on it as a fulcrum. A suitable type of thrust ball bearing connection is indicated in Fig. 1 of the drawing.

Connected to pressure pipe 71 is a manually controlled by-pass conduit 80 which leads to a valve casing 81 in which is a valve 82 which controls the flow of fluid through conduit 80. Connected to valve casing 81 on the discharge side of valve 82 is a waste pipe 83 which may lead to any suitable point, for example, back to a tank 84 from which pump 73 draws its supply of fluid. Valve 82 is cone-shaped and cooperates with a valve seat in the form of a thin-edged orifice which may be provided by forming an opening in a comparatively thin plate or partition member 85. With such an orifice arrangement the flow through it will be proportional approximately to the square root of the pressure. Valve 82 has its spindle 86 connected by a link 87 to an operating lever 88 which moves over a quadrant 89 and is adapted to be fixed in adjusted positions by a latch 90 which engages notches in quadrant 89. At 91 is a pipe for conveying fluid which leaks past piston 66 from cylinder 67 to pipe 83, and at 92 is a pipe which connects discharge chamber 44 to pipe 83.

Connected to turbine 5 at a point of intermediate pressure is a conduit 93 through which low pressure elastic fluid may be supplied to turbine 5 to operate it as a mixed pressure machine. Such low pressure elastic fluid may be obtained or gathered from non-condensing engines or turbines such as are used to drive auxiliaries, or from other sources as is well understood, and it will do useful work in the lower pressure stages of turbine 5 which is a condensing unit. In conduit 93 is a valve 94 having its stem 95 connected to a piston 96 which is located in a cylinder 97. Valve 94 is biased to closed position by a spring 98 which is located in cylinder 97 and bears against piston 96. Connected to cylinder 97 beneath piston 96 is a pressure pipe 99 which leads from the cylinder 35 of the motor which operates valve 9. A discharge pipe 100 is connected to cylinder 97 for carrying away leakage past piston 96.

Connected to pressure pipe 71 is an automatically controlled by-pass conduit 101 which leads to a valve casing 102 in which is a passage 103, the area of which is controlled by a cone-shaped valve 104 having a stem 105 which is pivotally connected to lever 60. Leading from valve casing 102 is a discharge pipe 106 which may lead back to tank 84 or to some other suitable place.

The operation is as follows:—Assume that turbine 5 is running at a desired

speed, valves 7, 8 and 9 being open to permit the admission of high pressure elastic fluid, valve 94 also being open to admit low pressure elastic fluid. The pressure pump 73 will be operating at a speed proportional to the speed of the turbine and will supply fluid under pressure through pipe 71 to the under side of piston 66 to maintain it in a position to hold valve 9 open to a predetermined extent. At the same time fluid supplied through pipe 71 will be by-passed through pipe 80 past valve 82 to waste pipe 83 through which it flows back through tank 84. Also, fluid from pipe 71 will be by-passed through pipe 101 past valve 104 to waste pipe 106. The valve 82 will have been set by means of hand lever 88 for a predetermined turbine speed, and valve 104 will stand in a certain position depending on the adjustment of floating governor lever 60 which in turn depends upon the extent to which valve 9 is opened. Valve 47 is held open and valve 49 is held closed by the lever 51. Pressure pump 73 is supplying fluid to inlet chamber 43 of the pilot valve casing 38 through pipe 46 and valve 47. Pilot valve 56 covers ports 40 in the pilot valve sleeve 39. Valve 94 in low pressure conduit 93 is held open by fluid pressure on the lower side of piston 96 which fluid pressure is conveyed to the piston through pipe 99 and is the same pressure which acting against piston 34 in cylinder 35 is serving to hold valve 9 open against the action of spring 36. With the elastic fluid turbine 5 operating at the speed for which hand lever 90 is set the various parts will be in a state of equilibrium. The pressure pump 73 supplies fluid continuously through pipe 71 and such percentage of it is by-passed through pipes 80 and 101 as to maintain a constant pressure in pipe 71 and under piston 66. The speed governor 77 is set to not come into play until a certain predetermined speed is reached which is greater than that for which the fluid operated governor is set. In other words, speed governor 77 is in the nature of an emergency governor and comes into play only in case of excess speed. At normal speeds it remains inactive, the upper end of stem 78 furnishing a fixed fulcrum for floating governor lever 60. If now it is desired to decrease the speed of turbine 5, hand lever 88 is moved to more nearly close valve 82. This means that less fluid can escape from pipe 71 through bypass pipe 80 with the result that the pressure under piston 66 builds up raising piston 66 against the action of spring 70. This turns floating governor lever 60 on pivot 79 thereby lowering the left hand end of lever 60 which pulls down the left hand end of lever 58 and raises pilot valve 56. Pilot valve 56 on being moved upward, uncovers ports 40 to a greater or lesser extent, there-

by connecting passage 38 by way of ports 40 to discharge chamber 44. As a result fluid from beneath piston 34 flows to discharge pipe 92, thus relieving to some extent the pressure under piston 34 and permitting spring 36 to push valve 9 toward closed position, thereby decreasing the amount of elastic fluid admitted to turbine 5 to effect a cutting down of its speed.

When floating governor lever 60 is turned on pivot 79 by an upward movement of piston 66, it will be noted that with the lowering of the left hand end of lever 60, valve 104 is moved toward closed position, thereby diminishing the flow of fluid past it to waste pipe 106. As a result the pressure in pipe 71 and hence under piston 66 will be built up more rapidly than would otherwise be the case because of the less amount of fluid which can escape past valve 104 with the result that piston 66 will be more quickly moved against the action of spring 70.

When piston 34 is moved by spring 36 to bring valve 9 more nearly to closed position, such movement turns bell crank lever 62 on its pivot thereby turning lever 58 on its pivotal connection with the upper end of rod 59 to lower pilot valve 50 and again cover ports 40. This constitutes a usual form of follow-up device for the pilot valve to prevent over-travel of the governor mechanism.

If a greater speed of turbine 5 is desired, then hand lever 88 is moved in a direction to open further valve 82 thereby permitting the more rapid escape of fluid from pipe 71 to decrease the pressure under piston 66 permitting spring 70 to pull it downward, thereby effecting an operation of the valve 9 in a direction to open it further, the operation being the same as that already described, except that it takes places in the opposite sense, pilot valve 56 being lowered to admit fluid pressure through ports 41 and 40 to the right hand end of cylinder 35 to move piston 34 toward the left against the action of spring 36.

With the hand lever 88 set for a given turbine speed if now the speed tends to increase or decrease due to changes in load or other causes, then the change in speed will cause an increase or decrease in the pressure supplied by pressure pump 73 thereby varying the pressure supplied through pipe 71 by either increasing or decreasing it depending upon the direction of the speed change. As a result piston 66 will be either moved upward due to increase in pressure, or permitted to move downward due to decrease in pressure, thereby operating valve 9 in the manner already described.

It will be noted when the valve gear is operated that valve 104 is always moved in a direction to assist the movement of piston 130

66; i. e., when the piston is being moved by increase in pressure, valve 104 tends to close to assist in increasing such pressure, while when piston 66 is being moved by 5 spring 70 due to a decrease in pressure, then valve 104 is opened further, thereby further diminishing the pressure in pipe 71 which assists spring 70 in moving piston 66. By this means I obtain a very sensitive governor 10 which can effect a movement of valve 9 from fully closed to fully open position with a very short range of movement of piston 66. This enables me to obtain a uniform action with a comparatively short spring 70 and 15 gives a governor which can maintain the speed substantially constant from no load to full load. Also the use of a thin-edged orifice in connection with valve 82 is important in obtaining a sensitive governor 20 and one having a narrow range for, as already pointed out, with such a governor the pressure increases approximately proportional to the square of the flow.

Speed governor 77 is normally inactive 25 but in case of excess speed, i. e., a speed above the range of the fluid-actuated governor, it comes into action to take control of the turbine, operating directly to move lever 60 which at such times pivots on the end 30 of piston stem 65.

As long as there is fluid pressure back of piston 34 to hold valve 9 open such fluid pressure serves also to hold valve 94 open for the admission of low pressure elastic fluid 35 to turbine 5; but whenever such fluid pressure on piston 34 is relieved to permit valve 9 to close then the pressure on piston 96 will be relieved permitting spring 98 to close valve 94. By this arrangement whenever valve 9 closes to shut off elastic fluid 40 to turbine 5, valve 94 will be closed also. Whenever the emergency speed governor mechanism is tripped to close valve 7 in the manner already explained, latch 54 is moved 45 from engagement with catch 53 thereby releasing rod 52 and permitting valve 47 to close and valve 48 to open. This serves to relieve the pressure on piston 34 directly to discharge pipe 92, thereby permitting 50 valve 9 and also valve 94 to close. It will thus be seen that whenever emergency valve 7 is closed valves 9 and 94 also are automatically closed. The closing of valve 9 makes sure that no elastic fluid will be admitted to the turbine should valve 7 stick 55 open or fail to close completely for any reason, and the closing of valve 94 cuts off the supply of low pressure elastic fluid to turbine 5.

60 In accordance with the provisions of the patent statutes, I have described the principle of operation of my invention, together with the apparatus which I now consider to represent the best embodiment 65 thereof, but I desire to have it understood

that the arrangement shown is only illustrative and that the invention may be carried out by other means.

What I claim as new and desire to secure by Letters Patent of the United States, is:— 70

1. The combination with a prime mover of a valve for controlling the admission of elastic fluid thereto, a pressure actuated governor for moving said valve, means for delivering fluid to said pressure actuated 75 governor at a pressure proportional to the speed of the prime mover, a by-pass comprising a thin edged orifice, a valve controlling said orifice, and a second by-pass, the discharge area of which is varied in a 80 direction to assist in movements of said pressure actuated governor.

2. In combination, a prime mover, a valve for controlling the admission of elastic fluid thereto, a fluid motor for said valve, a pressure actuated governor, a governor lever connecting the governor to said motor, pump means driven by the prime mover for supplying fluid to said governor at a pressure proportional to the speed of the prime 90 mover, a manually regulated valve for bypassing fluid from said pump means, and a valve moved by said governor lever for bypassing fluid from said pump means, said last-named valve acting in a direction to 95 assist the movement of said governor.

3. In combination, a prime mover, a valve for controlling the admission of high pressure elastic fluid thereto, a fluid motor for actuating said valve, a governor for said 100 motor, a valve controlling the admission of low pressure elastic fluid to the prime mover, said last-named valve being biased towards closed position, and fluid pressure actuated means connected to said fluid motor for holding said last-named valve open. 105

4. In combination, a prime mover, an emergency valve therefor, a control valve in series with the emergency valve, a conduit for admitting low pressure elastic fluid to 110 the prime mover, a valve in said conduit, and means for effecting the closing of said last named valve and said control valve when the emergency valve closes.

5. In combination, a prime mover, an 115 emergency valve therefor, a control valve in series with the emergency valve, a conduit for admitting low pressure elastic fluid to the prime mover, a valve in said conduit, fluid actuated pistons for opening said last 120 named valve and said control valve, and means for relieving the pressure on both said pistons when the emergency valve is tripped.

6. In combination, a prime mover, a conduit for admitting high pressure elastic fluid thereto, a conduit for admitting low pressure elastic fluid thereto, a valve in the first named conduit, a fluid actuated motor for moving it, a valve in the second named 125 130

conduit, a movable abutment connected to it, and means subjecting said movable abutment to the pressure of the fluid in said fluid actuated motor whereby said last named valve will be held open as long as there is fluid pressure on the motor to hold the first named valve open.

7. In combination, a prime mover, a conduit for admitting high pressure elastic fluid thereto, a conduit for admitting low pressure elastic fluid thereto, a valve in the first named conduit, a fluid actuated motor for moving it, a valve biased to closed position

in said second named conduit, a piston connected to said last named valve, a cylinder 15 for the piston, and a pipe connecting said cylinder to the fluid actuated motor whereby the pressure on said fluid actuated motor will serve to hold said second named valve open and when such fluid pressure is relieved to effect closing of the first named valve said second named valve will be permitted to close.

In witness whereof, I have hereunto set my hand this 25th day of May, 1920.

FRANK S. BENNETT.
